Inventor
George Walther,

By Toulmin & Toulmin

Attorneys

UNITED STATES PATENT OFFICE.

GEORGE WALTHER, OF DAYTON, OHIO, ASSIGNOR TO THE DAYTON STEEL FOUNDRY COMPANY, OF DAYTON, OHIO, A CORPORATION OF OHIO.

WHEEL.

Application filed July 5, 1922. Serial No. 572,838.

To all whom it may concern:

Be it known that I, GEORGE WALTHER, a citizen of the United States, residing at Dayton, in the county of Montgomery and State of Ohio, have invented certain new and useful Improvements in Wheels, of which the following is a specification, reference being had therein to the accompanying drawing.

10 My invention relates to casting and in particular to cast steel wheels.

It is the object of my invention to eliminate the use of the cope portion of the flask and the green sand therein together with the necessary moulding of the sand, and the handling of the flask containing it.

It is the object of my invention to provide mechanism to take the place of the cope which will permit of rapid and economical manufacture of cast wheels and similar manufacture of the parts substituted for the cope.

This part consists of a dry sand cope core member which may be readily and easily handled without the necessity of a crane or similar apparatus.

It is my object to provide a single member of this character with a pouring gate in place of the cope thus greatly shortening the time necessary for the assembling of the flask, green sand and cores.

Referring to the drawings:

Fig. 1 is a section through the assembled apparatus;

35 Fig. 2 is a section taken on the line 2—2 of Fig. 1;

Fig. 3 is a plan view taken on the line 3—3 of Fig. 1.

Referring to the drawings in detail, 1 is a bottom board, and 2 the drag portion of the flask mounted thereon.

Within the drag portion is the customary green sand 3. The hub core 4 is located upon the green sand centrally adjacent the drag portion 5 of the cores for the spokes and rim.

6 is the cope portion of the cores for the spokes and rim. 8 is the spoke portion, 9 is the rim portion and 10 is the hub portion 50 of the cope cap core which has an arbor 10 moulded therein with projecting radiating members 11 resting upon the top of the flask 2. These members are positioned on the flask by the pins 12. They are further 55 positioned and clamped by the clamps 13

which engage at three points as bearing points, the members 11 and the flange 14 of the flask. In order to lock these parts in engagement wedges 15 are provided.

A pouring cap 16 is provided of dry sand 60 and is held in place by a pouring cap ring 17.

The metal is poured in the opening 18 and fills the space around the hub core and the spoke and rim cores to form the wheel. 65

It will be apparent as the spoke and rim cores and hub core are placed into position all that it is necessary to do to complete the mechanism for pouring is to put the single cap structure into place positioning 70 it by the pins 12 and clamping it by 13 and 15 where, upon the locking of 16 and 17 the wheel can be poured.

It will be understood that I do not desire 75 to be confined to this specific adaptation of my invention, but comprehend within it suitable modifications which may be necessary to adapt it to varying conditions.

Having thus fully described my invention, what I claim as new and desire to secure by Letters Patent, is:—

1. In combination a flask consisting of a drag portion, a bottom board, green sand therein, hub, spoke and rim cores, cope cap core, means in said last mentioned core for 80 locating it with respect to the flask, means of clamping said locking means to the flask, and a pouring cap core and means to maintain last mentioned core in position.

2. In combination a drag portion of a 85 flask having green sand therein, a bottom board, hub, spoke and rim cores located in the flask said cores having cope and drag portions, a cope cap core having arbors therein and a plurality of projections therefrom, means on some of said projections for positioning the cope cap core, and means on some of said projections for locking said cope cap core to the flask.

3. In combination a drag portion of a 100 flask having green sand therein, a bottom board, hub, spoke and rim cores located in the flask said cores having cope and drag portions, a cope cap core, having arbors therein and a plurality of projections therefrom, means on some of said projections for positioning the cope cap core, means on some of said projections for locking said cope cap core to the flask, and a pouring 105 cap core.

4. In combination a drag portion of a flask having green sand therein, a bottom board, hub, spoke and rim cores located in the flask said cores having cope and drag portions, a cope cap core having arbors therein and a plurality of projections therefrom, means on some of said projections for positioning the cope cap core, means on

some of said projections for locking said cope cap core to the flask, the positioning means being located opposite one another and the locking means being located at three points equal distances from one another.

In testimony whereof, I affix my signature.

GEORGE WALTHER.
